BINDING OF BOOKLETS, CATALOGUES, OR
THE LIKE

Albert Edward Perkins, London, England

Application March 24, 1937, Serial No. 132,778
In Great Britain March 30, 1936

8 Claims. (Cl. 11—4)

This invention relates to the binding of booklets, catalogues and other publications on wire stitching machines and is more particularly concerned with saddle stitched booklets and the like.

5 In wire stitcher-feeding machines for inserting and stitching saddle-stitched work, sections of folded paper, hereinafter referred to as signatures, are placed on the stitching machine at a number of feeding stations, each of which is provided with a saddle bar for receiving the signatures, and a conveyor chain gathers the signatures together from each station and feeds the gathered signatures, with their covers, to a stitcher head where wire stitches are inserted 15 through the backs of the booklets or the like thus formed.

Booklets and the like bound and stitched in this way have the disadvantage that the covers are liable to be torn off, since they are only secured by the wire stitching. One of the objects 20 of the present invention is to overcome this disadvantage by applying a hot or cold adhesive to the back and/or sides of one or more of the inserted signatures, and essentially the outer signature, when travelling or stationary on the wire stitching machine and prior to the cover being laid on the gathered signatures, whereby the cover is adhesively secured automatically to the back of the outer signature in addition to being 25 stitched thereto with wire stitches.

30 Although the primary object of the invention is to secure the cover to the outer section of the booklet more securely than hitherto, it will be clearly understood that each or any of the inserted signatures may be adhesively secured to one another in the same way before the wire stitching operation is effected.

In order that the invention may be better understood one particular embodiment thereof will 40 now be described with reference to the accompanying drawing, but it must be understood that the construction and arrangement of parts, in the embodiment illustrated may be varied in many respects without departing from the spirit 45 and scope of the invention.

In the drawing Figure 1 is a side elevation showing the conveyor, feeding stations and a stitcher head of a wire stitching machine provided with adhesive applying means according to 50 the invention, and Figure 2 is a sectional view of a modified part of the adhesive applying means.

55 Referring to the drawing the machine comprises a plurality of saddle bars 2 for receiving the signatures 3 which are to be collected together and bound into book form and a conveyor chain 4 for collecting the signatures and conveying them to a device, indicated generally at 5, for applying adhesive to the back and/or sides of the outer signature and finally to a stitcher head 6 where wire stitches are inserted through

the backs of the booklets after the cover has been laid on. The adhesive applying device in its simplest form comprises a container 7 for the adhesive rigidly mounted above the conveyor chain 4 and provided with a roller 8 rotatably mounted in bearings in the walls of the container 7 and projecting through an aperture in the bottom of the container. The under side of the roller 8 lies in substantially the same horizontal plane as the upper edge of the saddle bar 2 or slightly below this plane so as to ensure that the back or folded edge of the signature contacts with the roller as it is slid off the saddle bar. The roller 8 may be plain or may be grooved, as shown on an enlarged scale in Figure 2, whereby 15 the sides as well as the backs of the signature 3 are coated with adhesive as will be clearly seen from the figure.

It is an essential feature of the invention that adhesive should be applied to the back and/or sides of the outer signature, that is the signature immediately adjacent the cover, so that an adhesive applying device 5 must necessarily be located between the last pair of saddle bars 2, that is to say between the saddle bar upon which the last signature is laid and that upon which the cover is laid. In certain circumstances, however, it may be desirable for each of the inserted signatures to be adhesively secured together and in this case an adhesive applying device 5 must 30 be provided between each pair of saddle bars.

In operation the individual signatures, which are to be bound into book form, are placed on the saddle bars 2 from which they are removed onto the conveyor 4 by pusher members 9 carried by the conveyor in known manner. The conveyor then carries the collected groups of signatures under the roller 8 which applies a coating of adhesive to the back and/or sides of the outer signature, as described above, whereupon the group 40 of signatures are carried past the last saddle bar from which the cover of the booklet is removed by the pusher members of the conveyor onto the adhesively treated outer signature of the group. The complete booklet is then carried by the conveyor to suitable stitcher mechanism 6 where the booklet is stitched with wire stitches in well known manner.

What I claim and desire to secure by Letters Patent is:—

1. A wire stitching machine for saddle stitching booklets, catalogues and the like comprising a stitcher head, a plurality of signature feeding stations, a saddle bar at each feeding station upon which signatures are positioned, a saddle bar for a book cover between one of said saddle bars and said stitcher head, a conveyor chain running below said saddle bars, pusher members upon said chain engageable with the signatures 55 upon the several saddle bars and conveying the 60

- gathered signatures and a cover therefor to said stitcher head to be stitched and means positioned between a signature saddle bar and said cover saddle bar for applying an adhesive to the back of at least the outer signature of the book prior to the cover being laid thereupon and stitched to the collated signatures.
5. A wire stitching machine for saddle stitching booklets, catalogues and the like comprising a stitcher head, a plurality of signature feeding stations, a saddle bar at each feeding station upon which signatures are positioned, a conveyor chain running below said saddle bars, pusher members upon said chain engageable with the signatures upon the several saddle bars and conveying the gathered signatures to said stitcher head to be stitched, and a plurality of means positioned respectively between signature saddle bars for applying adhesive to the backs of each of the signatures prior to the next succeeding signature being laid thereupon and stitched to the collated signature.
6. A wire stitching machine for saddle stitching booklets, catalogues and the like comprising a stitcher head, a plurality of signature feeding stations, a saddle bar at each feeding station upon which signatures are positioned, a saddle bar for a book cover between one of said saddle bars and said stitcher head, a conveyor chain running below said saddle bars, pusher members upon said chain engageable with the signatures upon the several saddle bars and conveying the gathered signatures and a cover therefor to said stitcher head to be stitched, and a grooved roller positioned between said signature saddle bar and said cover saddle bar, a container for adhesive having an aperture in the bottom thereof, said roller being mounted in said container and projecting through said aperture, whereby a coating of adhesive is applied to the back and sides of the outer signature prior to the cover being laid thereupon and stitched to the collated signatures.
7. A wire stitching machine for saddle stitching booklets, catalogues and the like comprising a stitcher head, a plurality of signature feeding stations, a saddle bar at each feeding station upon which signatures are positioned, a saddle bar for a book cover between one of said saddle bars and said stitcher head, a conveyor chain running below said saddle bars, pusher members upon said chain engageable with the signatures upon the several saddle bars and conveying the gathered signatures and a cover therefor to said stitcher head to be stitched, and a plurality of containers for adhesive, each having an aperture in the bottom thereof, said containers respectively being located between signature saddle bars and between the last of said signature saddle bars and said cover saddle bar, a roller mounted in each container and projecting through the aperture therein for applying adhesive to the back of each signature before the signatures are collated and prior to the cover being laid thereupon and stitched to the collated signatures.
8. A wire stitching machine for saddle stitching booklets, catalogues and the like comprising a stitcher head, a plurality of signature feeding stations, a saddle bar at each feeding station upon which signatures are positioned, a saddle bar for a book cover between one of said saddle bars and said stitcher head, a conveyor chain running below said saddle bars, pusher members upon said chain engageable with the signatures upon the several saddle bars and conveying the gathered signatures and a cover therefor to said stitcher head to be stitched, a plurality of containers for adhesive each having an aperture in the bottom thereof, said containers respectively being located between signature saddle bars and between the last of said signature saddle bars and said cover saddle bar, and a grooved roller mounted in each container projecting through the aperture therein for applying adhesive to the back and to a contiguous portion of the side of each signature.
5. A wire stitching machine for saddle stitching booklets, catalogues and the like comprising a stitcher head, a plurality of signature feeding stations, a saddle bar at each feeding station upon which signatures are positioned, a saddle bar for a book cover between one of said saddle bars and said stitcher head, a conveyor chain running below said saddle bars, pusher members upon said chain engageable with the signatures upon the several saddle bars and conveying the gathered signatures and a cover therefor to said stitcher head to be stitched, and a roller positioned between said signature saddle bars and

ALBERT EDWARD PERKINS.
